UNITED STATES PATENT OFFICE.

SEBASTIAN ZIANI DE FERRANTI, OF GRINDLEFORD, ENGLAND.

INTERCONVERSION OF KINETIC AND POTENTIAL ENERGY OF FLUIDS.

964,633.

Specification of Letters Patent. Patented July 19, 1910.

Original application filed December 16, 1907, Serial No. 406,802. Divided and this application filed December 28, 1908. Serial No. 535,335.

To all whom it may concern:

Be it known that I, SEBASTIAN ZIANI DE FERRANTI, a subject of the King of Great Britain and Ireland, and residing at Grindleford, in the county of Derby, England, have invented certain new and useful Improvements in and Relating to the Interconversion of Kinetic and Potential Energy of Fluids, of which the following is a specification.

This invention relates to the conversion of the kinetic energy of a fluid more or less into potential energy by means of nozzles, being a divided out application from Patent No. 948,213, and is applicable to fluid compressors, pumps and many other kinds of appliances.

It has hitherto been found that nozzles when applied for this form of energy conversion were extremely inefficient. I have found in nozzles as heretofore constructed that when the particles of fluid at high velocity entered the increasing area portion of the nozzle, the paths of the particles were substantially parallel to one another, so that the stream of flow did not efficiently fill the nozzle, owing to the fact that no lateral force was present to cause the divergence of flow. I have come to the conclusion that no such force can exist under the given conditions, and after careful investigation of this problem, I have found that a substantial portion of the fluid flows on with but little diminished velocity through the increasing area nozzle. It follows, therefore, that not only must the path be of increasing area portion but the projection of the high velocity fluid entering the same must be effected along straight divergent lines corresponding to the nozzle divergence, so that practically no change of direction of projection is imposed upon the fluid during compression. Although it is of greater importance to project the fluid into the increasing area nozzle along lines corresponding to its divergence, yet the same principle may also be applied in decreasing area portions of the nozzle when such are used.

My invention consists in a nozzle in which the conversion of the kinetic energy of a fluid into potential energy is effected by projecting the fluid along straight divergent lines into the increasing area portion in a radially outward direction.

My invention further consists in the improved nozzles to be hereinafter described.

In the accompanying drawing I have illustrated a sectional elevation of one form of nozzle constructed according to my invention.

In this nozzle the fluid is introduced through two oppositely disposed entry portions, *a*, and *a'*, of convergent form, and is diverted substantially at right angles to its original line of flow by means of a guide, *f*, into the increasing area part, *g*, which in this instance is formed of two disks, *h*, arranged substantially parallel to one another. The discharge into the increasing part of the nozzle takes place radially, the increase of area being obtained by the divergence of the radial lines of flow as the fluid is projected outward from the center of the nozzle. The fluid from the nozzle is discharged into an annular chamber, *i*, surrounding the conversion part of the nozzle. In some cases the guide piece may be dispensed with, the impact of the opposing jets causing the fluid to be projected into the increasing area portion along straight divergent lines. Again in other cases one of the opposite entry portions may be dispensed with, a suitable guide piece being disposed opposite to the discharge from the remaining entry portion, so as to divert the fluid and discharge it radially into the increasing area passage of the nozzle in a similar manner to that before described. The fluid has imparted to it the necessary velocity by any well known means, and after passing through the entry portion of the nozzle is discharged radially outward through the increasing area portion, in which the kinetic energy wholly or partly is converted into potential energy.

It will be evident that many modifications may be made in the details of construction of the nozzle which I have illustrated which is simply to be regarded as exemplary and not in any way restricting the scope of my invention.

Having now described my invention what I claim as new and desire to secure by Letters Patent is:—

1. In combination a casing having a disk-like path of increasing area formed therein, means for supplying fluid to the central portion of said disk-like path and directing it through said increasing area path in

straight divergent lines, together with means for leading the fluid away from the outer periphery of said casing.

2. In combination a casing having a disk-like path of increasing area formed therein, an inlet conduit of decreasing area, means for supplying fluid to said conduit, means for directing the fluid into said increasing area path in straight divergent lines, together with means for leading the fluid away from the outer periphery of said casing.

3. In combination a casing having a disk-like path of increasing area formed therein, an inlet conduit of decreasing area, means for leading fluid from said conduit so that it passes through said increasing area path in straight divergent lines, means for supplying fluid to said conduit, together with means for leading fluid away from the outer periphery of said conduit.

4. In combination a casing having a disk-like path of increasing area, an inlet conduit of decreasing area at right angles to said disk-like path, a conical member disposed in said conduit and adapted to direct the fluid into said increasing area portion in straight

divergent lines, together with means for leading the fluid away from the outer periphery of said casing.

5. In combination, a casing having a disk-like path of increasing area, together with means for leading fluid through said disk-like path in straight divergent lines.

6. In combination, a casing having a disk-like path of increasing area, means for introducing jets of fluid to said casing which coalesce and pass through said disk-like path in straight divergent lines.

7. In combination, a casing having a disk-like path of increasing area, means for introducing jets of fluid at opposite sides of said casing which coalesce and are then led through said increasing area portion in straight divergent lines, said means including a decreasing area nozzle.

In testimony whereof, I affix my signature in presence of two witnesses.

SEBASTIAN ZIANI DE FERRANTI.
